UNITED STATES PATENT OFFICE.

WILLIAM T. LEADER, OF MONMOUTH, ILLINOIS, ASSIGNOR OF ONE-THIRD
TO JOHN W. MATTHEWS, OF SAME PLACE.

STOVE-PIPE THIMBLE..

SPECIFICATION forming part of Letters Patent No. 238,131, dated February 22, 1881.

Application filed December 1, 1880. (No model.)

To all whom it may concern:

Be it known that I, WILLIAM T. LEADER, a citizen of the United States, residing at Monmouth, in the county of Warren and State 5 of Illinois, have invented certain new and useful Improvements in Stove-Pipe Thimbles; and I do hereby declare the following to be a full, clear, and exact description of the invention, such as will enable others skilled in the 10 art to which it appertains to make and use the same, reference being had to the accompanying drawings, and to letters or figures of reference marked thereon, which form a part of this specification.

15 My invention relates to stove-pipe thimbles; and the nature thereof consists in certain improvements in the details of construction thereof, whereby the thimble may be secured in the hole in the wall or other place, and 20 the stove-pipe secured to the thimble in such manner, also, that both attachments may be readily and easily made and detached.

25 In the accompanying drawings, which illustrate my invention, and in which the similar letters used as marks of reference apply to the like parts in all the figures, Figure 1 is a side elevation of my improved thimble with a section of stove-pipe in place therein. Fig. 2 is a sectional elevation of the thimble, stove- 30 pipe, and wall. Fig. 3 is a section in the line xx in Fig. 1. Fig. 4 is a detail view to be hereinafter referred to.

The construction and relative arrangement of the parts of the improvement and the adjacent parts of the common thimble and stove-pipe are as follows:

35 Letter A represents the thimble, which may be formed of a single cylindrical section of pipe, as shown in the drawings, or it may be 40 formed in any ordinary manner.

B is an annulus with any desired number of holes b. The annulus B is seated over the thimble, as shown in the drawings, and is held by the wall C on one side, and on its other 45 side by an exterior annular flange, a, on the thimble A. The annulus B may be placed on the thimble by passing it over the end farthest from the exterior flange, a, (when the thimble is not in the wall,) and may be removed by a 50 reverse proceeding. The annulus B may be formed as an exterior annular flange on the thimble, or attached thereto in any desired

manner, so that it will hold the thimble from being pushed inward in the hole in the wall; but I prefer attaching it as described, and so 55 that it can be removed from the thimble.

Ears D are attached to one end of the thimble, projecting as shown at Fig. 1. These ears D should be of light material, so that when the thimble is inserted in the hole in the wall 60 or chimney C, with the annulus B resting against the wall, the ears may be bent or turned down upon the wall, as shown at Fig. 2, and thus prevent the thimble from being withdrawn by any ordinary means until the 65 ears D are straightened.

E is a common stove-pipe, with ears e secured to its exterior, each having a hole, e', coincident with a hole, b, in the annulus B. Bolts F project through and from the holes 70 b, and when the stove-pipe is inserted in the thimble these bolts pass through the holes e' in the ears e, and nuts e'' may be screwed thereon to hold the stove-pipe securely in the 75 thimble.

By cutting the annulus B, as shown by dotted lines g at Fig. 3, the cut portions may be turned outward to form tongues, which may project through the holes e' in the ears e, and be turned down on the ears, as shown in Fig. 80 4, to hold the stove-pipe to the thimble.

I am aware that a thimble provided on its inner end with strips bent outwardly to embrace the inner surface of the chimney-flue, and at its outer end with a flange, which engages with a corresponding flange on the pipe-collar, and a removable collar, is old, and such I do not wish to be understood as claiming, broadly, as of my invention.

What I claim as new is—

90 The combination, with the stove-pipe thimble having ears D at one end and a flange, a, at the other end, of the removable annulus B, having a series of holes, b, and the stove-pipe having perforated ears e, and screw-bolts and 95 nuts for securing said parts together, substantially in the manner herein shown and described.

In testimony whereof I affix my signature in presence of two witnesses.

WILLIAM T. LEADER.
